UNITED STATES PATENT OFFICE.

ANDREW TEAS, OF NEWARK, NEW JERSEY.

MACHINE FOR CUTTING LEATHER, PASTEBOARD, &c.

SPECIFICATION forming part of Letters Patent No. 235,588, dated December 14, 1880.

Application filed April 24, 1880. (No model.)

To all whom it may concern:

Be it known that I, ANDREW TEAS, of Newark, in the county of Essex and State of New Jersey, have invented certain new and useful 5 Improvements in Machines for Cutting Leather, Pasteboard, and other Like Materials, of which the following is a specification.

My improvements relate to machines for cutting leather and other materials, wherein a 10 knife or knives is or are actuated to cut the material in curved or other outline, by means of a pattern or pattern-bar, past which said knife or knives travel. They are particularly applicable to a machine for cutting, skiving, 15 creasing, and polishing leather straps, for which were granted to me Letters Patent of the United States, numbered 217,428, and dated July 8, 1879, and will be described here in relation to parts of such a machine.

20 In machines heretofore made wherein a stationary pattern-bar has been employed to direct the knife or knives, the knife or knives not being susceptible of an oscillating motion relatively to the sides of the pattern to present their edges at all times in the direction of the cut, have effected cuts at an angle to the pattern with a more or less dragging or tearing action, which has proved very objectionable, especially with certain materials, and 25 notably with pasteboard.

The object of these improvements is to obviate this objection; and to this end they consist in the combination of a stationary pattern and a knife or knives adapted to be moved 30 along said pattern and directed by the same in cutting, and susceptible of oscillating or adjusting themselves so as to present their edges in the direction of the cut at all times.

They also consist in the combination of a stationary pattern and a disk-shaped rotary knife or knives directed by the same in cutting, and susceptible of oscillating or adjusting themselves so as to present their edges in the direction of the cut at all times.

45 They also consist in the combination of a pattern, a knife or knives directed by the same in cutting, and weights or springs for keeping them or their supports in contact with the pattern.

50 In the accompanying drawings, Figure 1 is a plan of a machine embodying my improve-

ments. Fig. 2 is a transverse section of the same. Fig. 3 is a perspective view of one of the knife-slides and knives, illustrative of a different method of securing a knife to its 55 slide. Fig. 4 is a side view of one of the knife-stocks and a disk-shaped rotary knife secured thereto, and Fig. 5 is a side view of one of the knife-stocks and knives shown in the machine illustrated in Figs. 1 and 2.

60 Similar letters of reference designate corresponding parts in all the figures.

A designates the bed or frame-work of the machine.

B designates a carriage, consisting in this 65 example of my invention of a rectangular frame arranged to travel along shears or ways a, extending from the bed or frame-work A, motion being imparted to it by any suitable means—such, for instance, as a rack or racks, b, and 70 a pinion or pinions, c, engaging therewith and actuated by a crank, d, on the shaft e, which carries said pinion or pinions.

C designates a pattern, consisting, as here 75 shown, of a stationary bar having a wavy or curved outline at the edges, and attached to the carriage B, to move therewith. It is preferably detachably secured, by screws f, or otherwise, to the carriage B, so that it may be removed and replaced by another, when desirable. 80

D designates knives (here shown as two in number) whereby the cutting is performed. They are mounted in slides S, fitting on a transverse bar, E, and impelled toward the pattern by weights F, attached to them by cords passing over pulleys G. In some cases I may employ springs in lieu of these weights and their appurtenances.

The knives shown in Figs. 1 and 2 are provided with round pivot-like shanks g, which 90 fit in cavities or bearings of corresponding shape in the slides S, in such manner as to be free to oscillate or turn part way round therein.

The shanks g may be formed in one piece with the knives, or may be formed in one piece 95 with stocks D', provided with recesses, in which the knives are fitted and secured by screws h. The latter construction is preferable, as it facilitates the tempering of the knives.

When the slides S are impelled toward the 100 pattern, as above explained, the knives bear against the edges of the pattern, and, owing

to their pivotal connection with the slides S, adjust themselves at different angles as the wavy or curved side of the pattern moves past them, and thus present their edges in the direction of the cut. This prevents any tearing or dragging action on the material being cut.

The knife D² shown in Fig. 3 has a shank, H, extending at right angles to it, and secured in a recess in a stock, D³, by a screw, i, serving also to secure this stock to the slide S' in such manner that it may oscillate or turn to enable the knife to properly adjust itself to the pattern.

The knife D⁴ shown in Fig. 4 consists of a disk provided with sharp edges, and connected, by a screw, k, to a stock, D⁵, having a pivotal connection with a slide. This knife is connected to the stock, so as to be free to rotate on coming in contact with the material to be cut, and is especially applicable to the cutting of pasteboard and similar materials. Preferably it fits a hub or nipple on the stock, so as not to cause undue strain on the screw.

Any suitable devices for throwing the weights out of action when it is not desired to hold the knives in contact with the pattern may be employed.

In many cases one knife only may be used.

By my invention I provide a machine whereby leather, pasteboard, cloth, and other like materials may be effectively cut by unskilled persons without danger of being torn.

What I claim as my invention, and desire to secure by Letters Patent, is—

1. The combination, in a machine for cutting leather, pasteboard, and other materials, of a stationary pattern and a knife or knives adapted to be moved along said pattern and directed by the same in cutting, and susceptible of oscillating or adjusting themselves so as to present their edges in the direction of the cut at all times, substantially as specified.

2. The combination, in a machine for cutting leather, pasteboard, and other materials, of a stationary pattern and a knife or knives adapted to be moved along said pattern, and susceptible of motion toward and from the pattern and of adjusting themselves at different angles relatively to the pattern.

3. The combination, in a machine for cutting leather, pasteboard, and other materials, of a stationary pattern and a disk-shaped rotary knife or knives directed by the same in cutting, and susceptible of oscillating or adjusting themselves so as to present their edges in the direction of the cut, substantially as specified.

4. The combination, in a machine for cutting leather, pasteboard, and other materials, of a stationary pattern and a knife or knives directed by the same, and weights or springs for keeping the knives or their supports in contact with the patterns, substantially as specified.

ANDREW TEAS.
